UNITED STATES PATENT OFFICE

2,121,430

FIXTURE

Edwin F. Guth, Webster Groves, Mo.

Application May 22, 1936, Serial No. 81,262

1. Claim. (Cl. 240—78)

This invention relates to fixtures, and with regard to certain more specific features, to electrical illuminating fixtures.

Among the several objects of the invention may be noted the provision of an electrical illuminating fixture which is adapted to provide both direct and indirect illumination; the provision of a fixture of the class described in which the direct illumination is confined and controlled in direction and intensity, to a desired degree; the provision of a fixture of the class described wherein the direct illumination is formed entirely of approximately parallel rays; the provision of an electrical illuminating fixture of the class described which is designed to provide ideal illumination for particular conditions, such as desk lighting; and the provision of an electrical illuminating fixture of the class described which is relatively simple and economical in construction. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claim.

In the accompanying drawing, in which are illustrated several of various possible embodiments of the invention,

Fig. 1 is a perspective view of a fixture embodying the present invention;

Fig. 2 is a vertical section of the fixture of Fig. 1;

Fig. 3 is a bottom plan view of the fixture of Fig. 1; and,

Fig. 4 is a vertical section similar to Fig. 2, illustrating an alternative embodiment of the invention.

Similar reference characters indicate corresponding parts throughout the several views of the drawing.

Referring now more particularly to Fig. 1, there is shown a fixture embodying the present invention, which is particularly suitable for ceiling mounting. Numeral 1 indicates a ceiling plate by which the fixture is attached. Depending from the plate 1 is a tube 2, at the lower end of which is secured an electric lamp socket 3 (see Fig. 2), which is enclosed by a cap 4. The socket 3 receives the upper end of an electric light bulb or lamp 5, of the customary pear-shape. The cap 4 preferably extends down a short distance over the neck of the bulb 5.

Supported by a plurality of circularly disposed

wires or the like 6, from the lower end of cap 4, is the fixture assembly comprising one of the principal features of the present invention. The assembly includes a reflector bowl 7, which is usually of truncated conical type, and which faces upwardly. The lower end of the bowl 7 is extended as a cylindrical portion 8, which may be provided with a series of ridges or set-back portions for the decorative effect obtained. The metal at the lower end of the cylindrical portion 8 is bent inwardly and somewhat back upon itself to provide a flange 9. Resting on the edge of the flange 9 is an upper, outwardly extending flange 10 of a cylindrical element 11, the lower edge of which is preferably likewise provided with an outwardly extending flange 12. At the points that they juxtapose, the flanges 9 and 10 are preferably welded or soldered or otherwise secured together, in such manner that a space is provided therebetween for receiving the anchoring ends of the wires 6, so that said anchoring ends are not visible from the exterior of the fixture. The fixture assembly is directly supported, it will be seen, by the engagement of the wires 6 with the flange 10.

Numerals 13 and 14 indicate short cylinders of thin material, such as sheet metal, that are supported on radially disposed bolts or the like 15, which are mounted on the outer cylinder 11. The number of cylinders such as 13 and 14 that are provided depends upon the type of direct light that it is desired to obtain from the fixture. For the majority of circumstances, the two cylinders 13 and 14, as shown, are usually sufficient.

The inner surface of the bowl 7 is usually silvered or painted to provide a highly reflecting surface. The bowl 7 reflects light from the bulb 5 upwardly from the fixture, ordinarily against the ceiling of the room, when it is reflected to the interior of the room providing an indirect light component. At the same time, direct light is able to pass from the bulb 5 downwardly through the circular regions between the cylinders 11, 13 and 14, providing a component of direct illumination. The cylinders 13 and 14, and the inner surface of cylinder 11, are ordinarily painted dead black, so that they reflect substantially no light. For this reason, they permit substantially only light rays closely approximately parallel vertical rays to pass therethrough. The cylinders 11, 13 and 14, it will be seen, comprise light-regulating louvres.

In a preferred form of the invention, the flanges 9 and 10 are provided with peripherally spaced light ports or openings 17 (see Fig. 1), through

- which a small portion of direct and reflected light from the bulb 5 can pass. Such light illuminates the exterior surface of the outermost louvre 11, to give the fixture an attractive appearance. 5 Some of this light further reflects from the inner face of flange 12 upwardly in order to illuminate the under surface of bowl 7, likewise for the sake of appearance. Some such reflection takes place even when the louvre 11 is painted dead black. 10 While the shape of the direct-light regulating louvres has been shown as circular, it will be apparent that this is not altogether necessary. For example, the louvres may be made in any form or shape, in order to obtain whatever shaped 15 region of direct illumination is required.

10 The combination of indirect light reflected from the ceiling of the room and direct light issuing from the louvres of the fixture of the present invention make the fixture ideally suited for such 20 purposes as desk illumination. For such illumination, it is ordinarily desirable that a relatively high intensity of indirect light be provided within the room containing the desk, but that an even higher lighting intensity, be provided on the 25 working surface of the desk. If the fixture of the present invention is located vertically above the desk, it will readily be seen that the direct 30 illumination from the fixture is provided on the working top of the desk, while the indirect illumination from the ceiling provides the necessary lighting intensity in other portions of the room.

30 The louvre system of controlling the direct illumination is highly satisfactory, as it can be made, at a minimum cost of parts, to provide a well-directed, direct illumination that is confined to a limited area. Further, with the fixture as thus 35 described, substantially all parts are made from sheet metal, which is most economical to handle and to finish in pleasing designs and colors.

40 Fig. 4 shows an alternative embodiment of the invention which differs from the embodiment already described only in that a bowl-shaped reflector 16 is provided around the neck of the bulb 5. The bowl reflector 16 is ordinarily secured to

the bottom edge of the cap 4. It is directed downwardly, so that the rays from the bulb 5 that normally would travel upwardly are at least in part reflected back downwardly toward the direct lighting louvres. Lighting for indirect illumination purposes then escapes from the fixture only between the outer edge of the bowl 16 and the outer edge of the bowl 7, and is somewhat reduced in volume, while at the same time, the volume of direct lighting, by reason of the directing effect of the reflector 16, is proportionately increased. 5

10 The embodiment of Fig. 4 has the added advantage of being capable, by suitable design, of being made vertically thinner than the prior embodiment, because the angle of the bowl 7 need not be so steep. 15

20 In view of the above, it will be seen that the several objects of the invention are achieved and other advantageous results attained. 25

As many changes could be made in carrying out the above constructions without departing from the scope of the invention, it is intended that all matter contained in the above description or shown in the accompanying drawing shall 25 be interpreted as illustrative and not in a limiting sense.

I claim:

In an electrical illuminating fixture, a light source, a reflecting bowl surrounding said light source and adapted to provide for indirect illumination, and louvre means at the base of said bowl, said louvre means being adapted to provide for direct illumination from said light source, said louvre means comprising a series of concentric figures formed of sheet-like material, and light ports at the base of said bowl providing for exterior illumination of the outermost louvre, said outermost louvre being provided with an outwardly extending flange adapted to reflect light 40 from the light ports to illuminate the under surface of said bowl. 35

EDWIN F. GUTH.
